UNITED STATES PATENT OFFICE.

GEORGE B. MALTBY, OF CLEVELAND, OHIO, ASSIGNOR TO CLEVELAND CAR SPECIALTY COMPANY, OF CLEVELAND, OHIO, A CORPORATION OF WEST VIRGINIA.

ROOF-CARLINE.

No. 824,941.

Specification of Letters Patent

Patented July 3, 1906.

Application filed October 25, 1905. Serial No. 284,273.

To all whom it may concern:

Be it known that I, GEORGE B. MALTBY, of Cleveland, in the county of Cuyahoga and State of Ohio, have invented a certain new 5 and useful Improvement in Roof-Carlines, of which improvement the following is a specification.

My invention relates to sheet or plate metal roof-carlines of the general class or type 10 which is exemplified in Letters Patent of the United States, No. 649,171, granted and issued to me and to Broderick Haskell (as assignee of two-thirds the right) under date of May 8, 1900.

15 The object of my present invention is to provide a roof-carline embodying the advantages of that Letters Patent No. 649,171 aforesaid, and the further advantages of increased strength without substantial increase of weight, and facilities for the reception 20 of a wood filler, if desired.

The improvement claimed is hereinafter fully set forth.

In the accompanying drawings, Figure 1 is 25 a side view in elevation showing one-half in length of a roof-carline embodying my invention; Fig. 2, a plan or top view of the same; Fig. 3, an end view as seen from the left; and Figs. 4, 5, and 6 transverse sections on the 30 lines *a a*, *b b*, and *c c*, respectively, of Fig. 1.

In the practice of my invention I provide a roof-carline which is formed of sheet or plate metal, preferably by being pressed or shaped in a die or mold. The body 1 of the 35 carline is integral and of channel form in transverse section and is suited to receive a filling 2, of wood, for the attachment of roof members, said filling-piece fitting between the side flanges of the carline and being secured thereto preferably by bolt, as shown in Fig. 6. The body is downwardly inclined 40 from its middle to each of its ends at such an angle as may be adapted to impart the desired pitch to the roof and in the instance shown is of uniform depth throughout, but it may, if preferred, be made of gradually diminishing depth from its middle portion toward its ends.

The ends of the body are turned into integral downwardly-projecting end flanges 1^a, which are adapted to abut against the side plates of the car-frame and to be secured thereto by horizontal bolts. As shown in full lines in Fig. 1, the body is made of suffi-

cient length to fit over the side plates, the 55 end flanges in such case abutting against the outer sides thereof; but, if preferred, its length may be such that the end flanges will abut against the inner side of the side plates, as indicated in dotted lines. The metal 60 blank from which the carlines are made is preferably cut out in such shape that when the carline is bent into desired form its vertical flanges shall be bent over into auxiliary flanges 1^b, which extend from its ends toward 65 its middle portion into which they gradually merge. The flanges 1^b are turned downwardly with the metal of the main portion of the body in forming the end flanges 1^a, thereby correspondingly increasing the bearing- 70 surface of the latter.

In order to impart increased strength and rigidity to the carline without substantial increase of its weight, a central rib or corrugation 1^c, which may either be made by pressing or folding the metal adjoining the longitudinal center line of the body into two downwardly-projecting plates in contact one with the other or preferably, as shown, into two separated plates presenting a U or channel section, is formed upon the body, said rib being of maximum depth at the middle of the carline and preferably, as shown, decreasing in depth toward its ends adjacent to which it merges into the body. It may, however, 85 be made of uniform depth throughout, if desired.

The construction described is, as before stated, adapted to receive a wooden filling-piece 2 for the attachment of the ridge-pole 90 and purlins; but, if desired, the vertical flanges of the body may be turned downwardly and outwardly to form a central seat 6 for the reception of a ridge-pole and similar lateral seats to receive purlins. 95

An improved carline substantially as above described is adaptable to use in connection with any known and preferred type of roof and, as will be obvious to those familiar with car construction, is simple, inexpensive, and presents increased strength and rigidity without any substantial increase in weight over those of the same general type heretofore known and used.

I claim as my invention and desire to secure by Letters Patent—

1. A sheet or plate metal roof-carline having a body of channel-section and an in-

tegral downwardly - depending longitudinal strengthening rib or corrugation extending from its middle portion toward each of its ends.

5 2. A sheet or plate metal roof-carline having a body of channel - section and an integral downwardly - depending longitudinal strengthening rib or corrugation, of U or channel section extending from its middle portion toward each of its ends.

10 3. A sheet or plate metal roof - carline having a body of channel - section, an integral downwardly - depending longitudinal strengthening rib or corrugation, extending from its middle portion toward each of its ends and downwardly - depending end flanges for attachment to a car-frame.

15 4. A sheet or plate metal roof - carline having a body of channel - section, an inte-

gral downwardly - depending longitudinal 20 strengthening rib or corrugation, extending from its middle portion toward each of its ends, auxiliary flanges turned on its vertical flanges and extending from each of its ends for a portion of its length, and downwardly - 25 depending end flanges turned on the metal of the body and the auxiliary flanges.

5. The combination of a sheet or plate metal roof-carline having a body of channel- 30 section and a downwardly - depending longitudinal strengthening rib or corrugation, and a filling of wood resting on the bottom of the body, on each side of the strengthening-rib, and secured to the side flanges of the body.

GEORGE B. MALTEBY.
